UNITED STATES PATENT OFFICE

REUBEN C. BAKER, OF COALINGA, CALIFORNIA, ASSIGNOR TO BAKER OIL TOOLS, INC.,
A CORPORATION OF CALIFORNIA

SCREEN PLUG FOR CORE BARRELS

Application filed December 24, 1927. Serial No. 242,363.

This invention relates to well drilling apparatus and particularly pertains to devices commonly termed core barrels which are employed to take samples or cores of the formation through which a well is being driven.

In general, these core barrels include a hollow drill barrel having a drilling shoe at its end which is run into the well either by a cable or at the end of a rotary drill pipe. 10 Within the drill barrel is an inner core barrel or tube relative to which the drill barrel is movable, so that the drill barrel may be operated to form a core and at the same time force the core tube over the core or sample to 15 recover it.

Prior to my invention, it has been common practice to leave the lower ends of these core barrels open while the barrel was being lowered into the hole. This often resulted in rendering the core barrel inoperative because 20 foreign material, such as cavings from the wall of the hole and other foreign matter, lodged in the core barrel, filling the same so that when the barrel was placed in operation 25 at the bottom of the well there was no space in the core barrel for the core to enter. Also, occasionally, foreign matter would pass upwardly through the core barrel and lodge under the valve at the top of the barrel which 30 was provided to permit the exit of fluid trapped in the barrel and hold this valve open, so that the circulating fluid would pass into the core barrel and wash out any core that might have been taken.

35 It is the principal object of the present invention to overcome this deficiency in prior structures, by providing a closure for the lower end of core barrels which would effectively obstruct the passage of material other than fluid into the barrel during the movement of the barrel to the point of operation in the hole, but which may be released after the barrel has reached the point of operation, so as to unobstruct the passage of a core into the 45 barrel.

In carrying out the invention into practice, I provide what I prefer to term a screen plug which is fitted to the lower end of the core barrel, and which will effectively obstruct the 50 passage of material other than fluid into the

barrel during the time that the barrel is being lowered into the hole. This screen plug, however, is of a diameter that it will pass up into the core barrel when released and I have so connected it to the core barrel that after the 55 latter has reached the point of operation, it will become disconnected from the plug so that the latter may pass upwardly into the core barrel and unobstruct the passage of a core therein.

60 One form which the invention may assume is exemplified in the following description and illustrated by way of example in the accompanying drawings, in which:

Fig. 1 is a fragmentary view in longitudinal section through a core barrel disclosing my improved device fitted thereto.

Fig. 2 is a similar view showing the improved device disconnected from the core barrel and moving upwardly therein as the 70 barrel penetrates the formation.

Fig. 3 is a perspective view of the improved device.

Referring more particularly to the accompanying drawings, 10 indicates a core barrel comprising an outer drill barrel 11 having a drilling shoe 12 at its lower end. This drilling shoe is described and claimed in my co-pending application entitled Drilling shoe, filed April 27, 1927, Ser. No. 186,908, while 75 the core barrel structure may be either of the type shown in my co-pending application entitled Rotary core barrel, filed April 27, 1927, Ser. No. 186,909, or in my United States Letters Patent #1,611,504, entitled Core barrel, issued to me December 21, 1926.

80 Arranged within the drill barrel 11 is a core barrel or tube 14 which is adapted to receive the core when the latter is formed by the drill barrel. The core barrel 14 advances 85 simultaneously with the drill barrel 11, but the latter is permitted a certain amount of movement relative to the core barrel so that it may penetrate the formation.

85 As before described, I intend providing a closure for the lower end of the core barrel to prevent the passage of material other than fluid into the core barrel during the passage of the core barrel down the hole to the point of operation. To accomplish this, I provide 100

a hollow cylindrical plug 15, the lower end of which is torpedo shaped as shown. The largest diameter of this lower end is slightly less than the inner diameter of the trimmer shoe 16 of the core barrel 14, so that it will snugly fit within the end thereof.

Above its lower end the plug 15 is reduced in diameter and at its upper extremity it is formed with an annular exteriorly projecting shoulder 17. This shoulder is adapted to be engaged by a plurality of flexible fingers 18 secured within the lower end of the core barrel at the inner periphery thereof. These flexible fingers 18 extend upwardly and inwardly and are outwardly yieldable, so that the larger portion of the plug may pass upwardly by the fingers and into the core barrel when released therefrom. It should be stated that these fingers 18 are for the purpose of pinching off a core inserted into the core barrel and to hold it in place while the core barrel is being removed from the well. Such a structure is described and claimed in United States Letters Patent #1,655,644, entitled Core retainer for core barrels, issued to me January 10, 1928.

Cooperating with the flexible fingers 18 in supporting the plug 15 at the lower end of the core barrel is a pin 19 which extends diametrically through the plug with its ends projecting a distance beyond the exterior surface of the plug, so that they will be engaged by the end of the trimmer shoe 16. Thus the plug will be held from dropping out of the core tube by the spring fingers 18, while the pin 19 will keep the plug from passing upwardly into the core tube.

In its lower end, the plug is formed with a plurality of restricted openings 20 so that fluid may pass upwardly into the core barrel. These openings are, however, not large enough to permit any obstructing substances from entering the core tube, while the latter is being lowered into place in the well.

In operation of the device, the plug is fitted to the end of the core barrel as illustrated in the drawings, and the latter is lowered into the hole. After reaching the point of operation, the weight of the core barrel resting on the ends of the pin 19 will shear the latter and disconnect the plug from the core barrel. The plug 15 will then be free to pass upwardly into the core barrel and will do so as the core is pressed upwardly into the core barrel. After the core has been taken, the entire structure is removed from the well and the core is removed from the tube. As the core is recovered, the plug will be removed and may be used in subsequent operations.

From the foregoing, it is obvious that I have provided a simple and efficient device, adding considerably to the successful operation of core barrels, which device is of simple and inexpensive construction.

I claim:

1. In combination with a core barrel, of a hollow plug adapted to fit within the lower end thereof to close the same, said plug being of a diameter whereby it may travel upwardly into the core barrel when released therefrom, said plug having a plurality of restricted openings formed therein to permit the passage of fluid therethrough, means on the plug engaging the core retainer in the core barrel to support the plug, means carried by the plug engaging the lower end of the core barrel to prevent the passage of the plug upwardly into the core barrel, said last-named means being fragile whereby it may be disrupted when the core barrel has reached the point of operation in a well so that the plug may be released from the core barrel and travel upwardly therein to permit the entry of a core.

2. In combination with a core barrel, of a plug fitted to the lower end thereof and effectively closing the same, said plug being of a diameter permitting it to pass upwardly within the barrel when disconnected therefrom, means on the plug engaging the barrel and normally preventing the plug from travelling upwardly into the barrel, said means being fragile and adapted to be rendered ineffective by imposing the weight of the core barrel thereon after the plug reaches the bottom of the hole.

3. In combination with a core barrel, of a plug adapted to fit within the lower end thereof to close the same, said plug being of a diameter whereby it may travel upwardly into the core barrel when released therefrom, means on the plug projecting transversely therefrom and engaging the core barrel and normally preventing the plug from passing upwardly into the core barrel, said means being fragile and adapted to be disrupted by imposing the weight of the core barrel thereon when the plug has engaged the bottom of the well.
